UNITED STATES PATENT OFFICE.

JOHN SORENSEN, OF RHINELANDER, WISCONSIN.

ADJUSTING MECHANISM FOR RESAWING MACHINES.

Application filed August 9, 1920. Serial No. 402,185.

To all whom it may concern:

Be it known that I, JOHN SORENSEN, a citizen of the United States, residing at Rhinelander, county of Oneida, and State of Wisconsin, have invented new and useful Improvements in Adjusting Mechanism for Resawing Machines, of which the following is a specification.

My invention relates to improvements in adjusting mechanism for re-sawing machines.

The object of this invention is to provide safe and easily controlled means for utilizing machine power to raise and lower the work table and conveyors of a re-sawing machine, the power transmitting connections for making the adjustment being under the control of the operator continuously during the adjusting operation. Also to provide means whereby movement is controlled in part by locking devices, which, when in locking position, prevent any change in adjustment, the power being applied thru friction wheels which slip when the resistance is excessive and therefore relieve the locking devices and table adjusting connections from excessive strain.

Further objects of my invention are to provide means whereby the power applying connections may be readily and quickly withdrawn from the table adjusting levers to permit the removal or replacement of saws, and then replaced in operative relation to such levers; to provide means whereby both the locking devices, and the power controlling device, may be simultaneously held in a desired position by a single operator, or the locking devices secured in a retracted position pending the operation of the power transmitting connections; and to provide means, whereby the power for adjusting the table and its associated parts may be derived from the overhead feeding conveyor and motion transmitted at a reduced speed suitable to the desired purpose.

In the drawings:

Fig. 1 is a side elevation of a re-sawing machine embodying my invention.

Fig. 2 is a plan view of the table and its associated feeding conveyor, partially broken away to show the associated cross lever for lifting the table, fragments of the saw being also illustrated.

Fig. 3 is a sectional view drawn generally on line 3—3 of Fig. 2.

Fig. 4 is a view in front elevation of my improved mechanism for actuating the table adjusting lever, the fragment of the table and feeding conveyors being shown in associated relation.

Fig. 5 is a sectional view drawn on line 5—5 of Fig. 1.

Like parts are identified by the same reference characters thruout the several views.

In its general organization the re-sawing machine illustrated in the drawings conforms to established practice. The work A is delivered to the saw over the rollers 1 and between a set of feeding conveyors. The lower feeding conveyor comprises a set of sprocket chains 2 provided with cross slats or bars 3. It travels over a table 4 having notches 5 therein to receive the sprocket chains 2 whereby the bars 3 may bear upon the table in a horizontal position while traveling across it. The side margins of the table are connected with slides 6 which are guided by the frame member 7 when the table is to be raised and lowered, by means of a table supporting lever 8 centrally pivoted to the table at 9.

One end of the lever 8 is fulcrumed to a bearing member 10 carried by the adjusting screw 11. The other end of the lever is loosely engaged in a stirrup 12 which is pivoted at 14 to a table adjusting lever 13. The latter is fulcrumed or pivoted to the frame at 15 and is locked in its various positions of adjustment by latch bars 17 (one on each side of the lever), each of which is adapted to engage a notched segment 18 from which it may be retracted by a handle 19. The segments 18 are of course secured to the frame of the machine.

The movements of the table are slight, but accuracy of table adjustment is important and it is also necessary that the rollers 1 over which the work is fed to the table conveyor should be such as to hold the work at the exact level at which the work supporting surfaces of the slats 3 travel. The same is true of the rollers 20 over which the work passes from the table. The adjustment of the table determines the thickness of the board to be cut by the band saw 22.

To raise or lower the rollers 1 and 20 simultaneously with the table adjustment, motion is transmitted from the lever 13 to these rollers thru the link rod 24, lever 25, link 26, bell crank 27, connecting bar 28, 110

bell cranks 29, rods 30, and bell cranks 31, the latter supporting the rollers 1 and 20. The shaft 32 upon which lever 25 is fulcrumed oscillates with the lever movement and 5 transmits motion to the opposite side of the table where a duplicate set of bell cranks and their connections are located. It is therefore obvious that any movement of the lever 13 will be simultaneously transmitted 10 to the table and to all of the rollers 1 and 20 to raise or lower them in unison. The connections are such that these movements of the table and rollers will be exactly equal and their horizontal position maintained.

15 In this application, the parts above described may be assumed to be old except as to the latch bars 17, segments 18 and levers 19, which are described and claimed in a separate application bearing even date here- 20 with and filed by me concurrently. But the above description is deemed necessary to a clear disclosure of my invention in its combination therewith and to fully explain its mode of operation.

25 In applying the invention herein claimed to the above described machine, I attach a bracket 35 to the frame bar 36 in which a driving roller 37 is journaled for actuating the upper conveyor, composed of the belts or 30 chains 38. The bracket 35 supports two sets of friction rollers 40 and 41, 42 and 43 respectively, the rollers 40 and 41 of the upper set being above the rollers 42 and 43 respectively. The rollers 40 and 43 have 35 shafts or trunnions which are journaled directly in suitable bearings in the bracket members, but the roller 41 has its shaft or trunnions 44 journaled in a forked or slotted lever 45 and the roller 42 has its shaft or trunnions 46 journaled in a forked or slotted lever 47. The lever 45 is pivoted to the frame at 48 near its upper end or ends. The lever 47 is pivoted to the frame at 49 near its lower end or ends and the unpivoted 45 ends of the levers 45 and 47 are linked together by a connecting bar 50 suitably notched to receive the ends of the levers. The notches are of such dimensions as to allow an adjustment of the levers therein 50 by means of adjusting screws 52 which have swivel connection with the bar 50 and threaded connection with the levers or vice versa.

55 A vertically disposed bar 55 is detachably connected with the table adjusting lever 13 by a link 56 and a removable pin 57, normally held in place by a swinging resilient arm 58. The upper portion of the bar 55 passes between the rollers 42 and 43 and between 60 the rollers 40 and 41, but normally without pressure contact with any of these rollers. The rollers 40 and 43 are continuously driven from the shaft 60 by means of a sprocket chain 61 and therefore inasmuch as 65 these rollers 40 and 43 are located on op-

posite sides of the bar 55, it is obvious that by pressing the bar 55 against the roller 40, it will be actuated in one direction, (upwardly), whereas if the bar is placed against roller 43 it will be pushed downwardly, since both of the rollers 40 and 43 revolve in the same direction on opposite sides of the bar. 70

The bar 55 may be pressed against either of these actuating rollers 40 or 43 by means 75 of the cooperating rollers 41 and 42, respectively, but owing to the cross connection of the levers 45 and 47, (bar 50), it is obvious that the pressure engagement of the rollers 41 and 42 with the bar 55 must 80 be alternate.

A convenient means for actuating these rollers 41 and 42 is comprised in the horizontally swinging, manually operated controlling lever 65 the motion of which is transmitted to the cross connection 50 thru its bell crank arm 66, link 67 and a lever 68 which is pivotally fulcrumed to the frame at 69. It is obvious that by moving the controlling lever 65 in one direction, the bar 90 50 will swing lever 45 towards the bar 55 and carry the roller 41 into pressure relation with it, thus pushing the bar 55 against roller 40, whereupon the bar, the table adjusting lever 13 and all of the parts with 95 which said lever 13 is operatively connected will be simultaneously lowered.

While the roller 41 is thus being pressed against the bar 55, the roller 42 will of course be carried away from the bar 100 whether in actual contact therewith or not at the beginning of the movement, but when it is desired to lower the table and associated parts, the controlling lever 65 will be swung in the opposite direction, thereby 105 swinging lever 45 outwardly from the bar 55, and lever 47 inwardly toward the bar. This carries roller 41 away from the bar and roller 42 into pressure contact therewith, pushing the bar against roller 43 on 110 the downwardly moving side thereof. Therefore the bar 55 and table adjusting lever 13 will move upwardly.

The latch bars 17 will of course be retracted from their respective segments 18 115 during the table adjusting movements above described but the arrangement is such that these latch bars 17 may be retracted with one hand by means of their operating handles 19, while the operator actuates the controlling lever 65 with the other hand. If desired, however, the operating handles 19 may be secured in the retracted position by ordinary catches or dogs 70 pending an adjustment of the table from one position 120 to another.

125 It is frequently desirable to remove the saw 22 and this must then be withdrawn forwardly from its supporting pulleys or drums. If permanently connected, the bar 130

55 would prevent the saw from being wholly withdrawn and therefore the pin or bolt 57 is made removable so that the link 56 may be readily detached from the table adjusting lever 13, after which the controlling lever 60 may be swung to a position for lifting the bar 55 and the latter will then be carried upwardly out of the way until the saw has been removed and replaced. The 10 bar 55 will then be lowered and reengaged with the table adjusting lever 13. The pin 57 may normally be held in position by the swinging spring plate 58 which is adapted to be manually pushed to one side to allow 15 the pin 57 to be withdrawn as above explained.

I claim:

1. The combination with the table adjusting lever of a re-sawing mechanism, of a 20 bar operatively connected with said lever, two sets of opposed friction rollers between which said bar passes, power connections for driving one roller in each set to rotate them in the same direction, said power 25 driven rollers being on opposite sides of the bar and each adapted to actuate the bar in a direction opposite to its movement when actuated by the other power driven roller, and a manually operable lever controlling 30 the position of the other rollers of the respective sets to selectively press the bar against either of the power driven rollers.

2. The combination with the table adjusting lever of a re-sawing mechanism, of a 35 vertically movable bar operatively connected with said lever, two sets of opposed friction rollers between which said bar passes, the manually operable lever having connections for actuating one roller of each set in 40 the direction of its associated roller for pressure engagement of such rollers with the bar, and power driven connections for one roller of each set, the power driven rollers of the respective sets being adapted to actuate the bar in opposite directions.

3. The combination with the table adjusting lever of a re-sawing mechanism, of a 45 vertically movable bar operatively connected with said lever, two sets of opposed friction rollers between which said bar passes, a manually operable lever having connections adapted to alternatively separate the rollers of one set while bringing those of the other set into pressure engagement with 50 the bar, means for actuating a roller in one set to move the bar upwardly when in pressure engagement therewith, and means for actuating one roller of the other set to move the bar downwardly when in pressure 55 engagement therewith.

4. The combination with the table adjusting lever of a re-sawing mechanism, of a 60 vertically movable bar operatively connected with said lever, a set of normally separated opposed friction rollers for actuating said

bar upwardly, another set of opposed friction rollers for actuating the same downwardly, a manually operable lever for alternatively adjusting said sets of friction rollers into and out of pressure engagement 70 with the bar, and co-operating manually adjustable means for locking the work table in a desired position of adjustment.

5. The combination with the table adjusting lever of a re-sawing mechanism, of a 75 vertically movable bar operatively connected with said lever, a set of normally separated opposed friction rollers for actuating said bar upwardly, another set of opposed friction rollers for actuating the same downwardly, a manually operable lever for alternatively adjusting said sets of friction rollers into and out of pressure engagement 80 with the bar, and co-operating manually adjustable means for locking the work table in a desired position of adjustment, said locking means and manually operable lever being disposed for simultaneous operation by one person.

6. In a re-sawing machine having a saw 90 operating horizontally above a work table, the combination with a friction bar and associated connections for varying the vertical distance between the saw and work table, of a set of power operated friction 95 rollers adapted for pressure engagement with the bar to move it in one direction, another set of power operated friction rollers adapted for pressure engagement with the bar to move it in the opposite direction, and means for manually and alternatively controlling the operation of said sets of rollers upon the bar.

7. In a re-sawing machine, the combination with table adjusting mechanism, of two 105 sets of friction rollers, a table actuating bar extending between the rollers of the respective sets, pivoted levers for actuating one roller of each set into and out of pressure engagement with said bar, a link connected to the levers of the respective rollers adapted to ensure their movement in alternation, means for adjusting the connection of said link with each lever to regulate the pressure of the associated roller upon said 110 bar, a manually operable member for transmitting motion to said levers through their link connections, and power transmitting connections for actuating one roller of each set.

8. The combination with the work table of a resawing machine, of a table adjusting mechanism, manually controlled power connections for actuating the table adjusting mechanism, and means for locking the adjusting mechanism, and releasing the locking means with one hand while controlling the power connections with the other.

9. The combination with the work table of a resawing machine, of table adjusting 139

mechanism, manually controlled power connections for actuating the table adjusting mechanism, and means for automatically stopping the motion of said table at a pre-
5 determined point, when said table is moved by said power connections, said last mentioned means being manually controllable.

In testimony whereof I affix my signature in the presence of two witnesses.

JOHN SORENSEN.
